UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed February 27, 1925. Serial No. 11,952.

This invention relates to improvements in stencil-card-writing devices for typewriting machines, as for example those disclosed in the patent to Elliott, No. 1,378,771, dated 5 May 17, 1921.

In said patent there is supported on the carriage a stencil-card-holding frame which is pivoted at the rear of said carriage and extends over the platen to the front thereof, 10 where there is suspended from it a stencil-card by a suitable clamp which grips the card at its upper edge. After attachment of the stencil-card, the holder is lowered to locate the card relatively to the printing 15 point of the platen, or, in other words, in its typing position. The line-spacing of the stencil-card is effected by a finger-wheel on the stencil-carrying frame, which is rotated by the typist after the typing of each line.

An object of the present invention is to expedite the operation of the device. To this end, one feature is the provision of means to enable the stencil-card to be attached to the holder by pushing it down into 20 the holder, thus avoiding the necessity of lifting the holder in order to attach the stencil-card. For this purpose the stencil-holder comprises two guide-fingers extending downwardly from the forward ends of said 25 holder, said guide-fingers having at their lower ends inturned portions or ears to engage the lower end of the stencil-card to raise said card during line-spacing operations of the stencil-holder. These fingers are 30 flexible, and are not required to hold the stencil-card against the platen, but merely to assist in line-spacing the stencil-card. To hold the card against the platen, there is provided a stationary guide which is elongated 35 so as to extend beyond the range of travel of the card-holding fingers, so as to prevent any possibility of collision of said fingers 40 with the ends of said guide.

Another feature of the invention relates 45 to means to expedite or facilitate the operations of line-spacing the card and returning the carriage. To this end, there is provided on the carriage a hold which may be engaged by the wrist of the typist, so that the 50 carriage may be returned by the wrist while the fingers are reaching back to the finger-wheel of the line-spacing mechanism to rotate it.

Another feature of the invention relates to the use of celluloid as a backing for the 55 stencil-card. The advantages of using celluloid between the stencil-card and the rubber platen of the typewriter are well known. It has been the practice to fasten a celluloid panel upon the platen, by means of screws 60 or other attaching devices. This has rendered it necessary to provide a specially built platen for stenciling purposes, which is an objection, and it has also rendered the platen unsuitable for ordinary correspondence 65 work, which is a further objection. Moreover it is necessary to rotate the platen backwardly preparatory to typing each card.

One of the objects of the present invention is to provide simple and inexpensive means 70 for overcoming these difficulties. To that end, the platen is silent during the line-feeding of the stencil; and against the platen is held a celluloid backing by means of a holding device mounted on the platen-frame. The celluloid backing is worn on one line only, notwithstanding that each stencil is 75 spaced line by line. The celluloid backing is in the form of a strip, and as soon as one line thereof becomes worn out, it may be advanced to bring a fresh line thereof into use, this advance being effected by the aid of the device which holds the strip against the platen, (the latter having a detent-wheel and detent to maintain the celluloid strip 80 in each position to which it is set by the revolution of the platen). A lengthy strip is provided, whereby a vast succession of successive renewals of wearing surfaces can 85 be brought into use at the printing line, and whereby, upon the removal of the entire strip when worn out, a fresh strip may be immediately and easily inserted, presenting a vast succession of new wearing surfaces. Thus the manipulation of a celluloid backing 90 is greatly simplified, and the cost is much reduced, and it becomes unnecessary to rotate the platen back preparatory to typing with every fresh stencil-card; and when it is desired to use the platen for correspondence work, it is only necessary to 95 pull off the celluloid strip.

The celluloid strip is held in place at the top of the platen by a special feed-roller, which may be released to permit insertion of 100 the leading edge of said celluloid strip under

said roller. By the co-operation of roller and platen the celluloid strip is fed up into use, line by line, as it becomes worn. Due to this feeding movement of the celluloid strip, there may be a tendency for said strip to bulge away from the platen. This bulge, however, may be taken up by releasing the roller at the top of the platen and pulling at the leading edge of said strip, to draw it tight against the platen. The strip may be inserted from the rear and passed forwardly under the platen and up around the same, the surplus strip hanging from the back of the carriage.

18 Provision is made to enable typing through the ribbon on the upper border of the card. To this end, a ribbon-controlling device is used comprising two keys, one of which is effective, when operated, to connect the ribbon-vibrating mechanism, so that the ribbon may be vibrated upon the actuation of the type-bars, the other key being effective, when operated, to disconnect the ribbon-vibrating mechanism.

25 A further feature of the invention relates to means comprising a handle, located in a convenient position, to be operated to release the card-holder from the line-spacing mechanism, so that it may be readily located in its lowermost position.

30 Other features and advantages will hereinafter appear.

In the accompanying drawings,

35 Figure 1 is a sectional side view of a portion of an Underwood typewriting machine, showing the invention applied thereto, the stencil-card being in its lowermost position for receiving the first line of typing, the section being taken on the line 1-1 of Figure 5.

40 Figure 2 is a diagrammatic view similar to Figure 1, showing the stencil-card in its highest position.

45 Figure 3 is a fragmentary front view, showing the ribbon-controlling keys.

Figure 4 is a perspective view, showing the fingers of the card-holder.

Figure 5 is a top plan view of the carriage, showing the device applied thereto.

50 Figure 6 is a front view of the parts shown in Figure 5.

Figure 7 is a front view, on a slightly smaller scale, showing the stationary guide relative to the card-holding fingers.

55 A stencil-card 10, upon which it is desired to type, is inserted bottom edge first, between card-holding pieces 11, in front of a platen 12, which receives the blows of type-bars 13. The card is laterally guided between bent portions 14, forming an integral part of the card-holding pieces, and are flared out at 15 to facilitate the insertion of the card. To further facilitate the quick insertion of the cards the card-holding pieces are also flared out at 16, thus forming

ing a chute for the cards, which rest at the bottom against an inwardly-extending bent portion 17.

The stencil-card usually consists of a paper-frame to reinforce and to keep in a flat condition a stencil-sheet in the center of the card. It is sometimes desirable to write with the use of the ribbon upon the frame of the card, and then withdraw the ribbon and cut upon the stencil-sheet with the bare type. To this end, mechanism is provided whereby the ribbon may be manually controlled to vibrate the ribbon when writing upon the frame, and to silence the same when cutting the stencil-sheet. To facilitate the operation, the regular mechanism in the Underwood machine is slightly modified in the present invention, to the end that instead of the operative having to control a special hand-lever to silence the ribbon, a key 18 at the end of a lever 19 may be used. The ribbon-vibrating mechanism is fully disclosed in the patent to F. A. Cook, No. 926,050, dated June 22, 1909, and need not herein be described. As modified in the present invention, the key 18 of the lever 19, which is rockably mounted on the frame of the machine, is operative to silence the ribbon, while the key 20 is operative to vibrate the ribbon. The

55 vibrating mechanism comprises a ribbon-vibrator 21 and a lever 22 to operate the latter, said lever being fulcrumed at 23 on a bracket 24 which is fast to the shift-frame 25. A pin 26 on the lever 22 engages with a slot 27 in a bracket 28, which is in turn operatively mounted on the universal bar 29. When the latter is operated, it causes the bracket 28 to move rearwardly, and to rock the lever 22, thus lifting the ribbon at

105 the striking of each type-bar. The bracket 28 is slidably mounted on an angular piece 30, and by means of linkage, not shown, is thrown out of engagement with the pin 26 when the key is depressed. To control the movement of the key 18, and to prevent its being depressed to a position where a

110 pin 31 will be thrown into engagement with a slot in the piece 32, thus vibrating the ribbon to render effective the lower portion 115 of the ribbon, there are provided a screw 33 fast on the frame of the machine, and a detent-spring 34 having two indentations co-operating with a pin 35 on the lever 19,

120 so that, when the lever is rocked to its neutral position, as shown in Figure 3, the pin 26 is pulled out of engagement with the bracket 28, and consequently the ribbon is not vibrated when the universal bar is 125 operated.

To facilitate the returning of the carriage, while line-spacing the card, the carriage is provided with a wrist support 36 which is fast to the carriage-frame by 130 means of screws 37. Upon rotating a

finger-wheel 38 to line-space the card, the back of the wrist is rested against the wrist-piece to return the carriage, thus simultaneously and with the same hand the card 5 may be line-spaced and the carriage returned. The wrist-piece is formed hollow to fit the shape of the wrist.

For line-spacing the card, there is provided mechanism whereby the free end of a 10 rockable support or frame 39 is raised by means of a cam 40 rotatably mounted on said frame and backed by an adjustably mounted supporting piece 41 mounted on the carriage through an arm 69. The rock- 15 ing frame comprises two end plates 42 joined together by a cross-bar 43, and is rockably mounted on a cross-shaft 44 at the rear of the machine. At the front the frame carries the card-holding pieces 11 fast thereto by 20 means of screws 45 fitting into holes 46. In this kind of device, one form of which is disclosed in said patent to Elliott, a spring, not shown, is loaded or wound up during the line-spacing of the card, as the finger-wheel 25 38 is rotated to store up power to automatically reset the card-holding pieces to their normal position. For holding the cam in place against the pressure of the restoring spring, there are provided a ratchet 47 and a 30 retaining pawl 48, the latter being rockably mounted on a screw 49 which is fast to the frame, and is controlled in its movement by a pin-and-slot arrangement 50.

It is sometimes desirable to differently 35 space the lines of typing upon the stencil-sheet, and to this end the relative position of the cam 40 and the ratchet 47 is shiftable by withdrawing a pin in the ratchet from engagement with one of the holes 51 in the 40 cam, and by engaging said pin with another hole. In this manner a different section of the ratchet having more or less teeth within the same space on the ratchet is brought into engagement with the pawl 48. It will be 45 noted that the teeth 52 of the ratchet 47 are of the same size to control the spacing between the first line of typing upon the frame of the card and the first line of typing upon the stencil-sheet. When it is desired to re- 50 store the frame to its normal position the pawl 48 is released by means of a finger-piece 53 fast thereto, and by the action of the restoring spring the cam 40 is reversely rotated to its normal position, as shown in 55 Figure 1, in which the cam is arrested by a pin 71 fast to the frame 39.

In order to protect the platen of the machine when the same is struck by the bare type, and to facilitate the cutting of the 60 stencil, there is provided a backing 68 in the form of a strip of comparatively hard material having a supply which may be inserted around the platen, down a rear table 54 under the platen co-operating with feed- 65 rolls 55, and up in front of the platen past

the printing point, and back, under pressure roll 56, and over a guide-piece 57. The pressure roll is rockably mounted upon a cross-shaft 58, and is held against the platen by the pressure of a spring 59 wound around 70 the shaft 58. In order to correct the bulging of the strip, and in order to laterally re-position the strip in case of accidental shifting, the pressure roll is provided with a finger-piece 60, which forms an integral part 75 of the bail 61, supporting the shaft 62 upon which the roll 56 is revolvably mounted.

It will be understood that the card-holding pieces are made of relatively thin material, and are practically flat when off the machine, as shown in Figure 4. In order to hold the card firmly pressed against the platen, there is provided a stationary plate 63 fast to the frame of the machine by means of screws 64. Said plate 63 extends beyond the travel of the card-holding pieces 11, so as to overlie the latter in all positions, and to hold the card slightly curved against the platen. The plate is further provided with a cut-out 65 to clear the types when striking the platen 12, which is mounted on platen-frame 66 upon a shaft 70 which carries at the end a finger-wheel 67 to line-space the backing around the platen as it gradually becomes worn out. 90

The backing 68 may be a comparatively long strip of celluloid having a supply at the rear of the machine, and, due to the nature of the material which wears out on one side only when the bare type cuts into the surface, 100 may be reversed, if desired, to double its wearing surface.

Variations may be resorted to within the scope of the invention, and portions of the improvements may be used without others. 105

Having thus described my invention, I claim:

1. In a front-strike stencil-card typing machine, the combination with a platen, of a liftable overhead frame, a carriage for said platen and frame, a card-holding frame connected at its top end to the front of said overhead frame and suspended in front of the platen and having side and bottom gages for a card, and a guard erected upon the framework of the machine and extending along the platen and confining said card-holding frame between the guard and the platen, and means for elevating said overhead frame step by step together with said card-holding frame, the latter being confined by said guard during all elevating and lowering movements of said overhead frame. 110

2. In a front-strike machine for typing on stencil-cards, the combination with a platen, of an overhead frame movable up and down relatively to the platen, a card-holding frame carried pendent by said overhead frame at the front of the platen, and a guard for maintaining said card-holding frame 120 130

in position with a card carried thereby 4
pressed against the platen in all up-and-down positions of the overhead frame.

3. In a front-strike machine for typing on stencil-cards, the combination with a platen, of an overhead frame movable up and down relatively to the platen, a pair of card-holding devices suspended at the front of the platen from said overhead frame, each of said devices including side and bottom gages for a card and outwardly-flared portions for entry of said card behind said flared portions and against the platen and thence to gaging position, and a guard for maintaining said devices with the card so held in all up-and-down movements of said overhead frame.

4. In a front-strike machine for typing on stencil-cards, the combination with a platen, of an overhead frame from the front end of which a stencil-card is suspended in front of the platen, a carriage for the platen and frame, a wrist-hold erected upon the right-hand portion of the carriage for returning the same to begin a new line of typing, a cam-mechanism for elevating said frame and card step by step, and a finger-wheel for operating said cam-mechanism, said wrist-hold being in such position relatively to the finger-wheel as to enable the operator to rotate said finger-wheel by his fingers while his wrist is returning the carriage.

5. In a typewriting machine, the combination with a platen and a letter spacing carriage therefor, of an arm-hold fixed to the carriage for returning the same to begin a new line of typing, and means for enabling an operator to line-space a work-piece through use of the finger of the same hand while his arm is returning the carriage.

6. In a typewriting machine, in combination, a carriage and a platen therefor, a stencil-cutting device operable to present a stencil-card to the printing field in front of the platen, said stencil-device including a support rockably mounted on a shaft at the rear of the machine, a card-holding device fast to the free end of the support, and means to line-space the card, said means including a cam operatively mounted on said support, a stud fast on the carriage and upon which the cam rests, and a finger-wheel to rotate the cam to raise the free end of the support and the card, and means for facilitating the return of the carriage, said last-mentioned means including a wrist-hold fast on the carriage in such position that as the

operator's wrist returns the carriage the fingers of the same hand may reach the finger-wheel to line-space the card.

7. In a typewriting machine, in combination, a carriage and a platen therefor, a stencil-device borne by said carriage and operable to present a stencil-card in front of the platen, said stencil-device including a frame rockably mounted on a cross-shaft at the rear of the machine, means for raising the free end of the frame, and card-holding pieces carried by said frame to support the stencil-card, said card-holding pieces moving with the carriage to letter-feed the card, and a guard fixed relatively to the carriage and co-operating with said card-holding pieces to hold the card against the platen.

8. In a typewriting machine, in combination, a carriage and a platen therefor, a stencil-device borne by said carriage and operable to present a stencil-card in front of the platen, said stencil-device including a frame rockably mounted on a cross-shaft at the rear of the machine, means for raising the free end of the frame, and card-holding pieces carried by said frame to support the stencil-card, said card-holding pieces moving with the carriage to letter-feed the card, and means fixed relatively to the carriage to hold the card in typing position against the platen, said last-mentioned means including a plate fast to the frame of the machine, overlying and overextending the card-holding pieces, said plate extending upwardly above the printing point, and having a cut-out portion in front of the type to clear the type-bars of the machine.

9. In a typewriting machine, in combination, a carriage and a platen therefor, a stencil-device borne by said carriage and operable to present a stencil-card in front of the platen, said stencil-device including a frame rockably mounted on a cross-shaft at the rear of the machine, means for raising the free end of the frame to line-space the card, said means including a cam revolvably mounted on said frame and an adjustable support in the form of an eccentric disk upon which the cam rests and revolves, said eccentric disk being supported on the carriage of the machine and adjustable to effect minute variations in the working positions of said frame, and means for holding said disk in any selected position about its eccentric axis, whereby to adjust the frame and thereby the card relatively to the printing line.

JESSE A. B. SMITH.
